United States Patent Office.

PURCHES MILES, OF NEW YORK, N. Y.

Letters Patent No. 104,184, dated June 14, 1870.

IMPROVED MACHINE FOR MAKING DOUBLE-POINTED TACKS.

The Schedule referred to in these Letters Patent and making part of the same.

To all whom it may concern:

Be it known that I, PURCHES MILES, of the city and State of New York, have invented an Improvement in Machinery for Making Double-pointed Tacks, &c., and the following is declared to be a correct description thereof.

This machinery is for cutting off a wire or rod diagonally at a given length, bending up the wire into a staple form in such a manner as to bring the points properly into line with each other, so that the double-pointed tack will drive in straight instead of the points being turned in opposite directions by the act of driving, as would be the case if said points were not turned or bent into line with each other.

In the drawing—

Figure 1 is a plan of the dies and mechanism for cutting off the wire and bending the same up to shape, and

Figure 2 is a vertical section of the same.

The bed-block *a* carries the bed-shear *b* that is adjustable by screws *c c*, and clamped by the screw *c'*.

The wire *d* is fed in by constantly-revolving friction-rollers or other suitable means; it passes under a guide, *e*, wherein is a yielding presser *e* that holds the wire while being cut, the said presser *e* and the shear *f* that act with the bed-shear *b* are moved by the follower of any suitable press or machine, and I remark that the arrangement of the mechanism is to be such that, as the shear *f* and presser *e* are lifted, the bending-punch *g'* will descend, and the reverse.

The mechanism for giving motion to the various parts may be of any desired character, and forming no part of this invention need not be further described.

The diagonally-cut end of the wire *d* is stopped by the gauge *h*, as said wire is forced along by the rollers that feed it in, and the blank *d'*, as it is cut, lies between the end of the bed-shear *b*, and an adjustable gauge, *k*.

The adjustable character of the gauges *h* and *k* and shears *b* and *f*, allow the blank *d'* being of a greater or less length as it is cut from the wire. Said gauge *h* may be of any desirable construction. I prefer the slotted block shown, as the end of the tack is not injured thereby.

A holding-jaw, *m'*, allows the wire *d* to slide under it, but prevents the wire being bent by the rising of the shear *f*.

The blocks *m m*, upon which most of the parts before-named rest, receive in grooves the bending-dies

o o, the contiguous ends of which are shown in the detached view, fig. 3.

The T-heads of these dies are provided with the springs *n* and regulating screws *P*.

The springs allow the said dies to slide and yield as the bending punch *g'* carries the blank *d'* down between the inner ends of said dies *o o*, and said springs throw the dies *o o* up against the sides of the punch *g*, above the ends of the double-pointed tack, bent up from the blank *d'* around said punch, so that the tack is pressed off the punch *g'* as that rises.

The screws *p* adjust the distance to which the dies *o o* may open.

The sides of the punch *g'* should be inclined slightly inward, as seen in fig. 2, to compensate for any spring in the tack after it is bent.

If the inner ends of the dies *o o* were square the tack would be bent up in the form shown in fig. 4, the points diverging; hence, when driven, the points will diverge still more, and the tack could not be withdrawn without injury to the wood, and the tack could not be used a second time.

My invention is made with a special reference to bending the rod or bar, so that these diagonally-cut points shall come into line with each other. To effect this, the ends of the dies *o o* are not square, but the rounding edges and faces of the dies that come below the straight sides of the blank *d'* are made fuller, or project slightly, as seen at 2 2, in order that the punch *g'*, in descending, shall bend up the wire at a slight oblique angle, so as to throw the points into line with each other, or as an adjunct to the method of bending herein described, the parts of the die and punch may be set sufficiently close to compress and extend the uncut edges of the limbs, and thereby throw the points toward the center and into line with each other, as seen in fig. 5.

What I claim as my invention is—

1. The shears *b f*, and gauge *h*, in combination with the bending-punch and dies, all arranged and operating substantially as and for the purposes set forth.

2. The dies *o o*, formed with oblique faces and sustained by and sliding in the block *m*, in combination with the punch *g* and shear for separating the blank with an inclined or diagonal cut, as specified.

Dated this 18th day of December, A. D 1869.
